UNITED STATES PATENT OFFICE.

ADOLPH R. RAMIG, OF CHICAGO, ILLINOIS, AND GEORGE H. RAMIG, OF TERRE HAUTE, INDIANA.

CAN OPENER.

Application filed April 16, 1925. Serial No. 23,541.

To all whom it may concern:

Be it known that we, ADOLPH R. RAMIG, of Chicago, in the county of Cook and State of Illinois, and GEORGE H. RAMIG, of Terre Haute, in the county of Vigo, in the State of Indiana, citizens of the United States, have invented a certain new and useful Improvement in Can Openers, of which the following, reference being had to the drawing accompanying and forming a part hereof, is a specification.

This invention relates to a device usable in opening cans containing food stuffs, as baked beans, cooked corn beef, salmon, tuna fish, crab meat, oysters, clams, and the like, or vegetables, as green peas, string beans, and beets, and fruits, as peaches, pears, and similar articles.

Among the objects of the invention is to obtain a can opener which will enable the operator to cut the wall or walls of a can adjacent to one end thereof, thereby separating what may be termed the top, (or bottom) of the can from said wall, or walls, in such manner as not to leave an inner annular flange on said wall or walls. An additional object is to obtain a can opener of the kind described by means of which one end of a can can be separated from the wall or walls thereof with equal facility whether said wall be cylindrical or oval, or whether said can is provided with rectangular walls having rounded corners. An additional object is to obtain a can opener which can be operated on a can of any size with the same effort by the operator. An additional object is to obtain a can opener which will not require the can to be held stationary while one end thereof is being removed therefrom. An additional object is to obtain a can opener of the kind recited which is easily operated, durable, not liable to become broken or to get out of order.

We have illustrated a can opener embodying our invention in the drawing referred to, in which

Fig. 1 is a side elevation, showing in cross section a portion of the upper end of a can to which the device is applied.

Fig. 2 is a top plan view of the device.

Fig. 3 is a bottom plan view; and

Fig. 4 is a sectional view of a vertical shaft and members mounted thereon, with

adjacent parts of the frame of the device, taken on line 4—4 of Fig. 1, viewed as indicated by arrows. 55

A reference character applied to designate a given part indicates said part throughout the several figures of the drawing wherever the same appears. 60

1 represents the frame of a can opener embodying the invention, which is preferably made of what is known to the trade as flat wire, and is provided with bends 2 and 3 to obtain table 4, which is substantially parallel 65 to the main body part of the frame. 5, 6, respectively represent parts of a sliding frame which is movably mounted on and underneath frame 1. Part 5 is provided with bends 7 and 8, to obtain members 9 and 10, at the ends thereof, which members are at right angles to the main body part of said part 5. Part 6 is provided with bends 11 and 12, to obtain members 13 and 14. 70 Member 13 is at right angles to the body part of said part 6, and member 14 is in a plane parallel to said body. 15 represents a slot at one end of member 14. 16, 17, respectively represent rectangular apertures in frame 1. 18 represents the upper end of member 10 75 of the sliding frame, and fits, to be movable in, aperture 17. 19 represents a rivet which extends through and is movable in aperture 16. The rivet 19 also extends through apertures provided therefor in parts 5 and 6, respectively, fitting tightly in said apertures, and is riveted, or flattened, at the end thereof against the under side or face of part 5, as at 20, Fig. 1. The portion of rivet 19 80 which extends through the apertures in parts 5 and 6, is preferably, of less diameter than the portion which extends through aperture 16, to obtain shoulder 21, so that when end 20 is flattened or riveted, as described the parts 5 and 6 are rigidly joined by said 85 rivet, without danger of forcing part 6 against the under face of frame 1. 22 represents a vertical shaft which is rotatably mounted in the body part of frame 1, and in table 4. 23 represents the upper end of shaft 22, said shaft being represented as bent to obtain a handle, and said handle affording means to manually turn said shaft. The lower end of the shaft 22 is illustrated as 90 screw threaded, as at 24, Fig. 4. 25 represents a roller which is provided with annular

100

105

- flange 26, at one end. 27 represents a wheel which is provided with ratchet teeth 28. Roller 25 and wheel 27 are, respectively provided with a screw threaded central aperture, said screw threads fitting closely to corresponding screw threads on shaft 22; and said roller and wheel are rigidly mounted on said shaft 22 by means of the co-acting screw threads, and the riveting of the end 10 of said shaft against the face of wheel 27, as at 29, Fig. 4.
- When vertical shaft 22, with roller 25 and wheel 27, rigidly mounted thereon as recited, are rotatably mounted in frame 1, the 15 roller is rotatable in the aperture provided therefor in table 4, and said roller also fits loosely in slot or recess 15, at the end of member 14 of part 6 of the movable frame. 30 represents a bolt which is rigidly secured in member 14 of part 6 of the movable frame, as by screw threads on said bolt fitting an aperture having corresponding threads in member 14, and by the nut 31. 32 is a roller, and 33 a cutter, which are mounted on bolt 30. 34 represents a lever which is manually turnable on bolt or rivet 35. Said bolt or rivet 35 is rigidly mounted on frame 1, and forms the fulcrum of said lever. 36, 37, represent cams, or cam surfaces, on one end of lever 34, and are illustrated as integral with said lever. Cam 36 is arranged to abut or come in contact with member 10 of part 5 of the movable frame of the device, and cam 37 is arranged to 35 abut or come in contact with the end 38 of part 6 of said movable frame, which is adjacent thereto. The position of the sliding frame comprising parts 5 and 6, on frame 1, is controlled by lever 34 and cams 36, 37; one of said cams moving said sliding frame in one direction and the other in the opposite direction, as lever 34 is turned on its fulcrum in one or the other direction.
- 39, Fig. 1, represents a portion of one 40 end of a can, and 40 a portion of a wall of a can. 41 represents the ordinary peripheral flange on the end of a can, and 42 the fold of the wall 40 on to said flange.
- To operate the device the lever 34 is 45 turned on its fulcrum into substantially the position illustrated in Fig. 3, thereby separating wheel 27 from roller 32 and cutter 33. The device is then placed on a can substantially as illustrated in Fig. 1, and handle 34 is then forced into substantially the position illustrated in Fig. 2. The peripheral edge of cutter 33 is thereby forced through the wall 40 of the can; the roller 32 is forced against said wall; and the teeth 28 55 of wheel 27 are forced against fold 42. Handle 23 is then turned clockwise, as viewed in Fig. 2, and by said turning the teeth 28 will turn the can and the peripheral cutting edge of cutter 33, will continuously 60 cut the wall 40. The turning of handle 23

is preferably continued until said cutter has cut said wall entirely around the can and bottom 39 thereby separated from wall 40.

If the can is rectangular in cross section, with rounded corners, the device is placed thereon in the manner last above recited, and as illustrated in Fig. 1; and handle 23 is turned on its fulcrum as above set out. The ratchet teeth 28 of wheel 27 will thereupon engage with fold 42, and move the 75 can along to a corner, and will then turn the can and move it along the next corner of the can; and upon continuous turning of said handle 23 will turn the can around and separate the bottom of the can from the 80 walls thereof.

During the operation of the machine as above described the member 9 of part 5 of the movable frame forms a guard protecting the operator from the cutting wheel 33. 85

We claim:

1. In a can opener, a frame comprising a bar provided with a table in a plane parallel to the plane of the body part of said bar, a shaft rotatably mounted in said frame, a handle on one end of said shaft and a wheel provided with teeth rigidly mounted on the other end of said shaft, a frame movably mounted on the first named frame, a cutting wheel rotatably mounted on said movable frame, and a guard on said movable frame arranged to be adjacent to the cutting edge of said wheel, in combination with a lever fulcrumed on said first named frame, and means on said lever arranged to control the position of said movable frame on said first named frame, and a roller rigidly secured to said cutting wheel.

2. In a can opener, a frame, a shaft rotatably mounted in said frame, means at one end thereof to manually turn said shaft and a wheel provided with teeth rigidly mounted on the other end of said shaft,

the body of said frame provided with a plurality of rectangular apertures, a two part frame movably mounted on said first named frame, a rivet extending through and movable in one of said apertures and extending through the two parts of said movable frame to rigidly join said parts, and one end of one of said parts extending through and movable in the other of said apertures, the other end of said last named part positioned to form a guard to the cutting edge of a cutting wheel, in combination with a bolt rigidly mounted on the other one of the parts of the two part frame, a cutting wheel and a roller rotatably mounted on said bolt, means to shift said cutter to and from the walls of the can, 120 said roller arranged to co-act with said wheel having teeth thereon.

3. In a can opener, a frame comprising a bar, said bar adjacent to one end thereof in a vertical plane and said end in a plane par-

- allel to the plane of the body part of said bar, to form a table, a shaft, a roller provided with an annular flange and a wheel provided with teeth, said roller and wheel 5 rigidly mounted on one end of said shaft and means on the other end thereof to manually turn said shaft, said shaft and roller rotatably mounted in the body part and table of said frame, respectively, in combination with an additional two-part frame 10 mounted on said first named frame, a cutting wheel and an additional roller rotatably mounted on one part of said additional frame, said additional roller arranged to co-act with said wheel having teeth thereon, the other part of said additional part arranged so that one end thereof forms a 15 guard to said cutting wheel, means to movably join said additional frame to said first named frame, and means to control the position of said additional frame on said first named frame.
4. In a can opener, a frame provided with rectangular apertures, and a lever fulcrumed on said frame, cams on said lever, in combination with an additional two-part frame, movably mounted on said first named frame, a bolt extending through one of said apertures and through the parts of said 20 additional frame, to rigidly join said parts, the ends of one of said parts at right angles to the body of said part one of said ends extending through the other of said apertures, and the other of said ends adapted to 25 form a guard to a cutting wheel mounted on said additional frame, said cams arranged to co-act with the parts of said additional frame to control the position of said additional frame on said first named frame.
- 30 5. In a can opener, a frame, a shaft screw threaded at one end thereof and means to manually turn said shaft at the other end thereof, said shaft rotatably mounted in said frame, in combination with a roller provided 35 with an annular flange at one end thereof and a wheel provided with teeth, said roller 40 and wheel provided with central screw threaded apertures corresponding with the screw threaded end of said shaft, and mounted thereon to turn therewith when 45 said shaft is rotated in a determined direction a rotatably mounted cutting wheel and roller, and means to shift the cutting wheel and roller to and from the can wall.
6. In a can opener, a frame provided with a table at one end thereof parallel with the body part of said frame, a shaft rotatably mounted in the body part of said frame and said table, said shaft provided with screw threads at one end thereof 50 and means to manually turn said shaft at the other end, a wheel provided with teeth and with a central aperture having screw threads corresponding with the screw threads on said shaft and mounted thereon to turn therewith when said shaft is turned in a determined direction, in combination with an additional frame movably mounted on said first named frame, a rotatably mounted cutting wheel and roller on said 55 additional frame, said roller arranged to co-act with said wheel having teeth thereon, with sheet metal interposed between them, and means to force said roller and wheel into co-acting relation with said cutting wheel extending through said sheet metal.
7. In a can opener, a frame, a lever fulcrumed on said frame and cams on said lever, a shaft and a wheel on said shaft rotatably mounted in said frame, in combination with an additional frame movably mounted on said first named frame, a cutting wheel and a roller rotatably mounted on said additional frame, a guard to said cutting wheel on said additional frame, said 60 lever and cams arranged to force said cutting wheel and roller into determined and co-acting relation with said first named wheel.

ADOLPH R. RAMIG.
